US0D1075301S

(12) United States Design Patent (10) Patent No.: US D1,075,301 S
(45) Date of Patent: * May 20, 2025

(54) BAG

(71) Applicant: Cato Industries, LLC, Covina, CA (US)

(72) Inventors: Zachary Ruzbasan, Corona del Mar, CA (US); Matthew Perez, Fremont, CA (US)

(73) Assignee: Agency Innovations LLC, Covina, CA (US)

() Term: 15 Years

(21) Appl. No.: 29/919,270

(22) Filed: Dec. 3, 2023

(51) LOC (15) Cl. 03-01

(52) U.S. Cl.

USPC D3/216; D3/289

CPC A45C 11/003 (2025.01)

(58) Field of Classification Search

USPC D3/201, 214, 216, 218, 230, 269, 299, D3/303

CPC A45C 1/04; A45C 1/06; A45C 1/08; A45C 11/00; A45C 11/24; A45C 11/182

See application file for complete search history.

(57) CLAIM

The ornamental design for a bag, as shown and described.

DESCRIPTION

FIG. 1 is a perspective view of a bag, showing our new design.

FIG. 2 is a back elevation view thereof.

FIG. 3 is a front elevation view thereof.

FIG. 4 is a top view thereof.

FIG. 5 is a bottom view thereof.

FIG. 6 is a right-side elevation view thereof.

FIG. 7 is a left-side elevation view thereof.

FIG. 8 is an alternative perspective view thereof.

FIG. 9 is an alternative back elevation view thereof.

FIG. 10 is an alternative front elevation view thereof.

FIG. 11 is an alternative top view thereof.

FIG. 12 is an alternative bottom view thereof.

FIG. 13 is an alternative right-side elevation view thereof; and,

FIG. 14 is an alternative left-side elevation view thereof.

1 Claim, 12 Drawing Sheets
